MACHINE FOR CRUSHING CANS

Harry Apprill, Hermann, Mo.

Application July 21, 1937, Serial No. 154,887

3 Claims. (Cl. 153—2)

My invention relates to treatment of cans by which after their contents have been removed they may be rendered incapable of being refilled.

The better grades of lubricating oils for use in automobiles are usually sold in sealed cans usually of quart size and it is important to the manufacturer that a can from which the contents have been removed may not be refilled as if refilled is likely to be refilled with inferior grades.

It is the object of my invention to provide a device by which a can from which the contents have been removed shall be so crushed as to be incapable of further use as a can and shall be so reduced in bulk that a considerable number of crushed cans may be stored in a bin or other receptacle.

With the above object and other objects hereinafter referred to in view my invention consists in and comprises the construction and combination of elements hereinafter described and claimed.

Referring to the drawings:

Figure 1 is a front view of a machine embodying my invention.

Figure 2 is a side view of the machine shown in Figure 1, looking to the left.

Figure 3 is a rear view of the machine shown in Figure 1.

Figure 4 is a top plan view of the machine.

Figure 5 is a fragmentary central sectional view.

Figure 6 is a detail sectional view of yielding means for disengaging a crushed can from the crushed head.

Figure 7 is a front view, and

Figure 8 is a side view partly in section of an end cutter.

In the drawings 1, 1, indicate vertical standards supported by base 2. 3 indicates an inclined drain board extending outward from the upper ends of standard 1, 1, and having drain opening 4. 5 indicates a storage chute extending upward from the upper ends of standards 1, 1, adapted to receive cans and to guide them into position between oppositely arranged end cutters 6, 7, each having a series of radial knives, which are carried respectively on the upper inwardly extending arms 8, 10, of slides 11, 12. These slides are mounted to be movable in a guide member 13 carried by arms 38, 39, extending upward from standard 1, having slot 14 through which extend pins 15, 16, carried respectively by slides 11 and 12. These pins extend into slots 17 at the upper ends of levers 18, 19, which are pivoted respec-

tively at 20, 21, on standards 1, 1, and have their lower ends pivoted to links 22, 23. These links are carried by head 24 of vertically movable rod 25 which is guided by guide 26 on the standards 1, 1, and guide 27 on base 2. To rod 25 between guides 26 and 27 is pivoted the end of foot lever 28 pivoted at 29 to standards 1, 1, and having at its free end foot rest 28. By depressing the free end of lever 28 the lower ends of lever 18, 19, are drawn towards each other causing their upper ends to move inward and, through pins 15, 16, on slides 11, 12, causing the cutter heads 6, 7, to move inward. On lever 28 on the portion extending from pivot 29 towards its free end is pivoted the lower end of rod 30, the upper end of which is threaded into the lower end of turn-buckle 31. Screwthreaded into the upper end of turn-buckle is rod 32 the upper end of which carries fork 33. The ends 34 35 of the arms of this fork are pivoted to arms 36, 37, which are each pivoted at its inner end to one of the upwardly extending arms 38, 39, carried by standard 1, 1, and at their free ends are pivoted to crusher head 40. Parallel with each of arms 36, 37, is an arm 41 pivoted at one end to one of the upwardly extending arms 38, 39 and at the other end to crusher head 40. By reason of these parallel arms the crusher head is ensured vertical movement. The crusher head is returned to elevated position after being depressed by foot lever 28, by spring 42 which is secured at one end to the foot lever and at the other end is secured to lug 43 on standard 1, 1.

As a can nears the lower end of chute 5 it is stopped by an arm of star wheel 45. This star wheel is carried by horizontal shaft 46 on which is carried ratchet wheel 47, the teeth of which are engaged by pawl 48 which is pivoted in upwardly extending arm 34. Pawl 48 is provided with an arm 49 below the plane of shaft 46 which extends forward into the path of a cam 50 carried by cutter carrying arm 9.

On the crusher head 40 are mounted springs 52 having at their free ends pins 53 extending through openings so as to be forced upward into the position in which it is shown in Figure 6 as the crusher head is forced downward to effect the crushing and as the crusher head rises the springs will press the can indicated at 54 away from the crusher head.

55 indicates a hook on the underside of drain-board 3 on which to hang a bucket to receive the oil as it drains through opening 4.

In operation cans being in place in chute 5 the lowermost one will rest against arms of the 55

star wheel 45. By depressing foot lever 28 arms 9 and 10 will be moved inward to cause cam 50 to act on arms 49 of pawl 48 to release the lowermost cam and permit it to drop into line with the cutter heads 6 and 7, being held in position by the arms of the star wheels 45 which by the release of pawl 48 are allowed to rotate one space.

As the cutter heads are allowed to move outward pawl 48 again engages a tooth of ratchet 46 to cause an arm of star wheel 45 to hold the can in position between and in line with the cutter heads. Lever 28 is then depressed and forces the cutter heads against the ends of the can. The radial knives of the cutter heads split the ends of the cans into tongues which are by the conical shape of the cutter heads caused to lie against the inside of the can wall and thus the resistance of these can heads to crushing of the can is done away with.

As the crusher heads move outward and the star wheel releases the can it slides forward into position beneath the crusher head 40. As the foot lever 28 is again depressed the crusher head is brought down on the can to flatten it out. It may then be removed by hand to the storage bin or otherwise disposed of.

Having thus described my invention, what I claim is:

1. In a machine for crushing cans including a frame having oppositely arranged cutter heads, means for moving the cutter heads toward each other to pierce the heads of the cans, flattening means for forcing the walls of the cans together

to flatten the same, means for conveying the cans from the cutter heads to the flattening means, means for positioning the cans successively in line with the cutter heads and the said flattening means.

5

2. In a machine for crushing cans comprising a supporting frame, conveyor means for supporting and guiding the cans through the said machine, oppositely arranged cutter heads arranged along the conveyor means for cutting the heads of the cans, means for collapsing the walls of the cans after they have been operated upon by said cutter heads, means for positioning the cans successively in line with and between the cutter heads and means for subsequently positioning the cans beneath the said collapsing means.

10

3. In a machine for crushing cans including a frame having oppositely arranged cutter heads, said cutter heads having conical faces carrying radial knives thereon, means for moving said cutter heads toward each other to cause them to pierce the heads of the cans and cut the said can heads into radial strips and to force the strips against the walls of the cans, means for flattening the walls of the cans, conveyor means for conveying the cans through the said machine, means for successively positioning the cans in line with the cutter heads and flattening means and means for operating said cutter heads and flattening means.
